UNITED STATES PATENT OFFICE.

RALPH W. MCNEILL, OF EDGEWOOD, PENNSYLVANIA. ASSIGNOR TO WESTINGHOUSE ELECTRIC & MANUFACTURING COMPANY, A CORPORATION OF PENNSYLVANIA.

SYSTEM OF CONTROL.

Application filed January 8, 1921. Serial No. 435,787.

To all whom it may concern:

Be it known that I, RALPH W. MCNEILL, a citizen of the United States, and a resident of Edgewood, in the county of Allegheny and State of Pennsylvania, have invented a new and useful Improvement in Systems of Control, of which the following is a specification.

My invention relates to motor-control systems and particularly to such systems as are employed with elevators, hoists and similar mechanisms.

The object of my invention is to provide means for controlling the speed of a hoisting motor and to provide automatic means for insuring graduated deceleration, or "slow-down" of the motor at either limit of travel of the car, prior to stopping.

It is proposed to provide a standard hoisting system with a switching mechanism operated by a centrifugal governor controlled in accordance with the speed of the hoisting drum. This switching mechanism is also controlled by a travelling-nut mechanism or a rotatable cam so geared to the hoisting drum that the cam will make approximately one revolution during the total travel of the car or for a predetermined number of rotations of the hoisting drum.

This switching mechanism controls the power supplied to the motor and will be actuated by the governor to produce a normal operating speed of the hoisting drum should the latter for any reason, exceed a predetermined operating speed. Also, in order to accomplish reasonable stops upon approaching the limits of travel, graduated deceleration, or "slow-down", will be similarly accomplished by the actuation of the rotatable cam.

My invention will be described in connection with the accompanying drawings in which—

Figure 1 is a diagrammatic view of circuits and apparatus embodying my invention.

Fig. 2 is a diagrammatic view of the hoisting mechanism.

Referring particularly to Fig. 1, a standard reversing control system is employed in connection with an electric motor. Any suitable control system may be employed. The system is also applicable to a steam hoist wherein the switching mechanism may control the steam throttle. However, in the

accompanying drawing, the switching mechanism is shown, for simplicity, as controlling main line or "reversing" switches.

Referring to Fig. 2, a hoisting drum 1 and a governor 2 are connected through gearing, 60 and the governor is actuated in accordance with the rotation of the hoisting drum, in a well-known manner. The governor is provided with switch contact members 4 and 5. Contact member 5 is attached to, and has the 65 same vertical movement, as rod 3 which is actuated by the governor balls. Contact member 4 is pivotally connected to rod 3 and normally moves, and is in engagement, with contact member 5. It is also capable of independent movement. A lever 6, which is pivotally connected to rod 3, is provided with a roller 7 that rides on a cam 8 which is rotated by the hoisting drum 1.

In Figure 1, a motor armature 9, which 75 is controlled by a master switch 10, is connected, by reversing contactors 11 and 12, to line conductors 13 and 14. An accelerating resistor 15 is controlled by a contactor 16. The motor field-magnet winding 17 is 80 connected in shunt relation to the armature 9.

In normal operation, the master switch 10 is actuated to the left to establish a circuit for the "up" direction of travel which may 85 be traced from the positive line conductor 13, through conductor 18, conductor 19, governor switch contact members 4 and 5, master switch contact members 20, 21 and 22, conductor 23 and coil 24, to the negative 90 line conductor 14. Contactor 12 is actuated to establish a main motor circuit extending from the positive line conductor 13, through conductor 18, contactor 12, conductor 25, armature 9, conductor 26, contactor 12, conductor 27, accelerating resistor 15 and conductor 28, to the negative line conductor 14. An accelerating contactor 16, with its coil 95 31 connected across the armature terminals, is actuated in a well-known manner, in accordance with the counter electromotive 100 force of the armature, to shunt the accelerating resistor 15 at a predetermined motor speed. A circuit for the motor field-magnet winding 17 extends from the positive line 105 conductor 13, through conductors 18, 19 and 34, field-magnet winding 17 and conductor 28 to the negative line conductor 14.

It may be assumed that the motor is now operating at normal speed, and contact mem- 110

bers 4 and 5 "float" with the movement of rod 3, in accordance with the motor speed. If, for any reason, a predetermined or dangerous speed is attained, the rod 3 is lowered, causing lever 6 to "tilt" a sufficient amount to lift contact member 4 out of engagement with contact member 5. The circuit of actuating coil 24 of contactor 12 is broken and the latter opens the circuit of the motor. Upon the restoration of normal speed, the power circuit is automatically restored by the engagement of contact members 4 and 5. Cam 8 rotates somewhat less than 360° for a total travel of the hoist. Approaching either limit of travel, the roller 7 rises on an inclined portion of the cam to disengage contact members 4 and 5. Power is cut off and the motor speed is reduced, the governor speed is correspondingly reduced and rod 3 is raised until lever 6 is sufficiently near to level position to restore contact members 4 and 5, when power is again applied momentarily, if the end of travel has not been reached. Finally, when the desired point of travel is attained, power is cut off by other means, such as hatchway limit switches of known character. In this system, the hoist never falls short of the desired level, since power is intermittently applied as long as required. Nor can the hoist exceed the proper level, since, upon approaching the limit at high speed, the governor rod 3 has an initial low position. Consequently, the cam disengages contact members 4 and 5 earlier than is the case when the speed is normal, power is cut off earlier and remains off until the speed is properly reduced. Power is again applied only if necessary to drive the hoist to the desired level. Actuating the master switch 10 to the right establishes a circuit to close contactor 11 and thereby reverse the rotation of the motor, in a well-known manner, after which the operation of the system is as previously described. If it is desired to operate the hoist more slowly than the normal rate or to decelerate at a rate lower than normal, such operation may be accomplished by intermittently opening and closing the motor circuit by means of the master switch. The automatic governor mechanism does not interfere with such operation so long as the speed is within the predetermined limit and the hoist is between the terminal limits. It is evident that I have disclosed means for controlling the speed of a hoisting or similar mechanism in which the controlling means is reduced to the simplest practical form, combining the speed-governing elements with means for limiting the car travel. This system is particularly advantageous in that accurate terminal stops are accomplished independently of varying load or speed conditions.

I claim as my invention:—

1. The combination with a motor-operated reciprocating device and speed-governed means for limiting the rate of operation thereof, of means comprising said limiting means for restricting the operation of the device to a predetermined range of movement. 70
2. The combination with a motor operated reciprocating device and a centrifugally operated switch for controlling the motor circuit, of means, comprising said switch, for limiting the speed of the motor to insure a predetermined operating movement of said device. 75
3. The combination with a motor and a switch for controlling the motor circuit, of a centrifugal governor operatively connected to said motor for actuating said switch, and additional means comprising a cam operatively connected to said motor for actuating said switch and said governor. 85
4. The combination with a hoisting mechanism comprising a winding-drum and a motor operatively connected to the drum, of a switch actuated in accordance with the speed of rotation of said drum, and a rotatable cam operatively connected to said drum for actuating said switch to control the speed of said drum. 90
5. The combination with a hoisting drum and means for operating the drum, of a switch actuated in accordance with the speed of said drum to control said operating means, and a rotatable cam operatively connected to said drum for actuating said switch within predetermined hoisting limits. 100
6. The combination with an electric motor and a switch for controlling the motor, of a hoisting drum operatively connected to said motor, a centrifugal governor operatively connected to the drum for actuating the switch and a rotatable cam operatively connected to said drum for actuating said switch in accordance with the position of said governor to maintain in effect a power supply for said motor during deceleration. 110
7. The combination with a motor-operated reciprocating device and a speed-responsive switch for limiting the rate of operation thereof, of means for automatically actuating said switch to limit the range of movement of said device. 115
8. The combination with a motor-operated reciprocating device, a switch and speed-responsive means for controlling said switch to limit the rate of movement of said device, of means co-operating with said speed-responsive means to automatically actuate said switch to insure a predetermined range of operating movement of said device. 120

In testimony whereof, I have hereunto subscribed my name this 27th day of December 1920.

RALPH W. McNEILL.
